UNITED STATES PATENT OFFICE.

HERBERT TOWLE WESTON, OF BEATRICE, NEBRASKA.

COUNTER.

No. 818,591.

Specification of Letters Patent.

Patented April 24, 1906.

Application filed March 9, 1905. Serial No. 249,317.

To all whom it may concern:

Be it known that I, HERBERT TOWLE WESTON, a citizen of the United States, residing at Beatrice, in the county of Gage and State of Nebraska, have invented new and useful Improvements in Counters, of which the following is a specification.

My invention relates to counters for indicating various data, &c., relating to the progress of one or a series of games; and it is more particularly designed for use as a bridge-whist counter.

The object of the invention is to provide a simple and attractive device of this character having a series of sliding devices coöperating with suitable headings whereby desired data relating to the game may be preserved as long as wished.

Another object is to employ folding means for operating the slides, whereby the counter can be placed within a pack of cards and present only flat faces to those cards contacting with it.

A still further object is to provide a counter which conforms in contour with playing-cards such as ordinarily used, so as to enable it to be placed in a box or other holder with the cards.

With the above and other objects in view the invention consists of certain novel constructions and combinations of parts, herein-after more fully described, and pointed out in the claims.

In the accompanying drawings I have shown the preferred forms of my invention.

In said drawings, Figure 1 is a front elevation of my improved bridge-whist counter. Fig. 2 is a section on line 2 2, Fig. 1. Fig. 3 is a section on line 3 3, Fig. 1. Fig. 4 is a detail view of one of the slides. Fig. 5 is a rear elevation of a modified form of counter. Fig. 6 is a central vertical section therethrough, and Fig. 7 is a view showing this modified form of counter opened. Fig. 8 is a perspective view of the counter, the parts being represented as assembled, with the slides omitted. Fig. 9 is a section of the device along the length of a slide or strip.

Referring to the figures by numerals of reference, 1 is a card similar in size and contour to playing-cards ordinarily employed, and the back of this card 1 may be suitably decorated, so as to look like the cards with which it is used. Printed or otherwise indicated along the front face of the card near one edge are suitable designating-words, such

as "Bridge-Whist Counter." Parallel lines 2 extend longitudinally upon the card and are subdivided to form columns 3. These columns may be provided with designations of any desired kinds. In the present instance I have shown them designated by the words "Points," "Honors," "Totals," "Rubbers," and "Games." Preferably three parallel slots 4 are under the "Points" column, three of these slots are under the "Honors" column, and four of these slots are under the "Total" column. Two slots are under the "Rubbers" column, and one or more are under the "Games" column. Apertures 5 are formed in each column between the ends of the slots 4 and the column-designating words, and these apertures align with the slots, as shown. These apertures are produced by slitting the card 1 to form bands 6, which are integral with the card and extend from side to side of the apertures. These bands may be glued or otherwise affixed to a backing-card 7, which is arranged back of the card 1, and those portions of card 1 between the slots 4 are also preferably affixed to card 7, except along the edges of the slots. Elongated parallel pockets are thus formed, said pockets aligning with the affixed bands 6 and the apertures 5. In each of these pockets is slidably mounted a strip 8, of cardboard or other suitable material, and the side edges of this strip are overlapped by the edges of the slot 4, back of which it is located. The strip 8 extends over the band 6, aligning with its pocket, and is visible through the aperture 5, formed above said band. Each strip has a flexible tab 9 secured to it near its lower end, and this tab is slightly less in width than the slot 4, so that it can be folded down into said slot when not in use. Numerals, arranged successively from "0" to "5" or higher, are indicated upon each strip, the character "0" being normally visible through the aperture 5.

It will be understood that the strips 8 can be manipulated to indicate any desired number under each column-heading, according to the number of strips aligning with the column. All of the strips normally rest with their characters "0" in the apertures 5. If it is desired to indicate one game, the tab 9 of the strip 8 in the "Game" column is raised from its slot 4 and by grasping it the strip can be slid longitudinally in its pocket until the numeral "1" appears in the aperture 5. All of the strips 8 are manipulated in this manner

and after the proper adjustment the tabs can be pressed back into the slots 4. When the tabs are in this position in the slots the entire device can be placed within a pack of 5 cards and will present flat surfaces to the adjoining cards.

While I preferably construct the counter of two cards 1 and 7, glued together, I can, if desired, make the device in the form of a 10 folder, as shown in Figs. 5, 6, and 7. By referring to said figures it will be noticed that the face portion 10 has an integral back 11, formed at one edge and provided with slits 12. A flap 13 is formed at the opposite edge of 15 the portion 10 and has a tongue 14, adapted to project into the slits and hold the back 11 in closed position. With this form of counter access may be had to the interior of the device at any time, and therefore the strips 8 20 can be replaced if worn or broken.

In the foregoing description I have shown the preferred forms of my invention; but I do not limit myself thereto, as I am aware that modifications may be made therein without departing from the spirit or sacrificing the advantages thereof, and I therefore reserve the right to make such changes as fairly fall within the scope of my invention.

Having thus fully described my invention, 30 what I therefore claim as new, and desire to secure by Letters Patent, is—

1. A counter comprising a face portion having suitable headings, slots and apertures, strips slidably mounted in the slots and apertures, 35 a band in each aperture extending under a strip, all of said strips being overlapped and retained by the edges of their slots, and a tab upon each strip and in its slot.

2. A counter comprising a face portion having headings thereon and slots and apertures under the headings, said headings being respectively "Points," "Honors," "Totals," "Rubbers" and "Games," strips slidably 45 mounted in the slots and apertures, a band in each aperture extending under the strip working therein, all of said strips being overlapped and retained by the edges of their slots, and a tab upon each strip and in its 50 slot.

3. A counter comprising a slotted body portion, a strip slidably mounted back of and retained in position by the edges of the slot, and a tab upon the strip and adapted to be 55 folded into the slot.

4. A counter comprising a slotted face portion having apertures alining with the slots,

a band in each aperture, a strip slidably mounted back of each slot and aperture and upon the band in its aperture, and a flexible 60 tab upon the strip and adapted to fold into the slot of the strip.

5. A counter comprising a face portion having parallel slots therein and apertures alining with the slots, said slots and apertures being suitably designated, a strip slidably mounted back of each slot and aperture, 65 said strip having successively-arranged numerals upon one face, means for holding the strip in its aperture and a flexible tab upon 70 each strip and adapted to fold into its slot.

6. A counter comprising a slotted face portion, a backing portion connected thereto, strips slidably mounted between said portions and having consecutively-arranged numerals thereon, and a flexible tab upon each strip adapted to fold into the slot of its strip. 75

7. A counter comprising a face portion having suitable headings thereon and slots and apertures under the headings, a backing 80 portion connected to the face portion, strips slidably mounted in the slots and apertures, means for holding the strips in the apertures, each strip having consecutively-arranged numerals upon one face, and a tab upon each 85 strip adapted to fold into the slot of its strip.

8. A counter comprising a face portion having headings thereon and slots and apertures under the headings, a backing portion and a flap integral with the face portion, said 90 flap adapted to engage and hold the backing portion, strips slidably mounted in the slots and apertures, means for holding the strips in the apertures, and a tab upon each strip adapted to fold into the slot of its strip. 95

9. A counter comprising a face portion having headings thereon and slots and apertures under the headings, said headings being respectively "Points," "Honors," "Totals," "Rubbers" and "Games," a backing-strip 100 connected to the face portion, strips interposed between the backing-strip and face portion and visible through the slots and apertures, means for holding the strips against displacement laterally, and a tab upon each 105 strip and extending through one of the slots, said tabs being adapted to fold into their respective slots.

In testimony whereof I affix my signature in presence of two subscribing witnesses.

HERBERT TOWLE WESTON.
